United States Patent Office

Des. 217,646
Patented May 19, 1970

217,646

WRITING INSTRUMENT

Walter J. De Groft, Glen Ellyn, Ill., assignor to Sanford Research Company, a corporation of Illinois

Filed June 24, 1968, Ser. No. 12,486

Term of patent 14 years

Int. Cl. D19—06

U.S. Cl. D74—17

FIG. 1 is a side elevational view of a writing instrument embodying my new design, the other sides being similar in appearance;

FIG. 2 is an end elevational view taken from the left-hand side of FIG. 1; and

FIG. 3 is an end elevational view taken from the right-hand side of FIG. 1.

I claim:

The ornamental design for a writing instrument, as shown.
